W. HENRISCH

SAFETY FOUNTAIN PEN

Filed March 10, 1923

INVENTOR:
BY *Wilhelm Henrich*
Wm Wallace White
ATTY.

UNITED STATES PATENT OFFICE.

WILHELM HENRISCH, OF GODESBERG, GERMANY.

SAFETY FOUNTAIN PEN.

Application filed March 10, 1923. Serial No. 624,063.

To all whom it may concern:

Be it known that I, WILHELM HENRISCH, a citizen of Germany, residing at Godesberg, Rhineland, Germany, have invented new and useful Improvements in Safety Fountain Pens, of which the following is a specification.

The safety fountain-pen forming the subject of the present invention is of the kind 10 distinguished by the feature that the act of revolving the cap automatically pulls forth or pushes back the nib-holder. But, while heretofore the cap was always screwed on the barrel of the fountain-pen by means 15 of a screw thread cut on the outside of the barrel, such screw-thread providing the means of exerting the pull necessary for hermetically sealing the cap on the barrel, the present construction does away with 20 this exterior screw-thread, besides affording a highly accelerated motion of the nib-holder, and, of course, the nib inserted in same.

The invention is characterized by a screw- 25 stem centered in the cap engaging a cylindrical nib-holder, provided on its cylindrical surface with a channel following a spiral course and gliding along a peg reaching into same, the longitudinal motion 30 thus obtained acting in one direction toward sealing the barrel by means of the cap and, in the other, toward sealing the junction of the nibholder and barrelmouth when the nib or pen is used in writing. Both ends, 35 it will be noticed, are attained without the use of a special screwthread, the means of attaining them consisting simply in flattening the course of the spiral screw channel and thus obtaining the necessary purchase 40 for exerting either a pull or a thrust, the one being required in sealing the barrel by means of the cap, the other coming into play when the cap is taken off and the pen protrudes for writing, and all issues must be 45 closed except the feed-channel.

A further special advantage of fountain-pens according to the present invention consists in the way the filling of the barrel is effected. All that is necessary is, in unscrewing the cap, to exert on it a longitudinal pressure. The consequence of such pressure being to increase the friction of the peg in the spiral course of the nib-holder, the effect will be to unscrew the stem of 55 the cap from the nibholder and prevent the latter from rising, that is, following the

cap. With the nib holder inside of the barrel the latter is open and the ink is filled into same in the way customary with safety fountain-pens. The cap is then screwed in place and when unscrewed again for writing will be found to function in the manner intended.

In the drawings accompanying and forming part of this specification—

Figs. 1 and 2 are partly sectional side views of a pen embodying one form of the invention, Fig. 1 showing the cap in position on the barrel, said cap being omitted from Fig. 2;

Fig. 3 is a vertical sectional view illustrating a modified form of pen, the pen point or nib being shown in withdrawn or inoperative position and the cap in place; and

Fig. 4 is a view similar to Fig. 3, but showing the pen point in operative position and the cap removed.

In the form of pen, shown in Figures 1 and 2, *a* is the nibholder, *b* being the nib or pen attached in the usual manner, the nibholder being provided with spiral screw course *c* into which a peg or projection *e* reaches from the inside of the barrel *d*. The peg *e* may be secured in a ring or annular 80 guide *f* fastened in the barrel. The cap *g*, the interior surface of which is smooth and glides on the smooth barrel, is provided with a central stem threaded at its free end *h* and engaging a female thread cut 85 into the top of the nibholder *a*. A rotary motion being given to the cap *g*, such motion is communicated to the nibholder owing to the screw-stem connecting the two 90 parts and the nibholder, owing to the spiral 95 groove and the fixed peg reaching into same, receives a longitudinal motion upward.

Referring now to Figures 3 and 4, which is to say, the second arrangement of parts, it will be seen that the spiral groove *c'*, instead of being located on the surface of the nibholder *a'* is transferred to a separate tubular part *m* placed in the bottom of the shaft or barrel and, if so desired, made as an integral part of the plug or stopper *p'*. The nibholder *a'* is provided with an extension stem *n*, the end of which glides in the tubular part *m* and is fitted with a peg *e'* reaching into the spiral groove *c'* of part *m*. A second peg *o* on the stem *n* serves as a stop 100 relieving the peg *e'* of any excessive strain it may be exposed to. With the nibholder in

its bottom position both pegs e' and o rest against terminal stops of part m . It will be easily understood that the action of the different parts, that is to say their functioning, is identical in both arrangements. Particularly is this the case as to the spiral groove, for, the one shown in the tubular part m has the same intermediate steep course as the one surrounding the nibholder of Figures 1 and 2, and the same flattened course at both its ends. Thus, in both arrangements the top and bottom flat courses serve toward gaining a purchase, while the intermediate steep part of the spiral brings about rapid action.

It is believed that the operating of the device will be obvious from the foregoing description. In either form, as soon as the nibholder has arrived at its extreme outermost position, as shown in Fig. 4, continued rotary motion of the cap serves to unscrew the stem from the nib holder. The pen is thus in its operative position ready for use, the top end of the nib holder sealing the mouth i of the barrel and thus preventing the ink from escaping except through the feed duct usually provided in the nib holder. The nib holder is caused to return to its innermost, or inoperative position by placing the cap over the pen and rotating said cap to cause its stem to engage the threaded opening in the nib holder. As soon as said stem is screwed "home" in said opening, the nib holder will rotate with the continued rotation of the cap, which rotation, owing to the pin and spiral slot connection between the nib holder and the barrel, will cause said nib holder to descend into the barrel. It will be noted that the spiral groove or slot in both forms of the device is materially flattened at both ends, as indicated at c^1 and c^2 . The purpose of this is to exert greater friction on the cooperating pin and thus positively retain the pen at either of its extreme positions. When the barrel is to be filled, the cap can be removed without raising the pen to its operative position. This is accomplished by exerting a downward

pressure on the cap, as indicated by the arrow k in Fig. 1, while rotating the cap in the reverse or anti-clockwise direction. This downward pressure increases the friction between the spiral slot and the peg or pin cooperating therewith and thus permits the unscrewing of the stem h from the nib holder, as will be obvious. The barrel can then be filled with ink in the usual manner by the use of a dropper, whereupon the cap can be replaced in the manner hereinbefore described. In the form shown in Figs. 1 and 2 the ink passes from above the nib holder through the channel or duct l shown in dotted line in said figures, through which duct, when the pen is in use, the ink flows to the nib.

The arrangement shown in Figs. 1 and 2 may be supplemented by making the plug p a screw-plug to be unscrewed for filling the barrel from the end.

What I claim as my invention, and desire to secure by Letters Patent, is the following:

A safety fountain pen, comprising a barrel having an open end, a nib holder having a feed duct and movable longitudinally in said barrel and adapted to close the same while leaving the feed duct unobstructed, one of said members having a spiral groove of less pitch at its ends than at the intermediate portion and the other member having a peg projecting into said groove whereby upon rotation of the nib holder relatively to the barrel the nib holder will be reciprocated within the barrel and supported thereby throughout its movement, a cap detachably connected to said nib holder, the connections between the barrel and nib holder and between the nib holder and cap being such that when the nib holder is at its lowermost position, further rotation of the nib holder will draw the cap into closer contact with the open end of the barrel thereby to hermetically seal the same.

In testimony whereof I have signed my name to this specification.

WILHELM HENRISCH.
